UNITED STATES PATENT OFFICE

2,176,108

METHOD AND APPARATUS FOR PHOTO-
GRAPHIC IMAGE PRODUCTION

Philip Stanley Smith, Camden, N. J.

Application July 11, 1936, Serial No. 90,118

37. Claims. (Cl. 88—16.6)

This invention relates to photographic reproduction and more particularly to improvements over the methods and apparatus disclosed in United States Letters Patent Nos. 1,927,925 and 5 2,025,731, of Ludwig M. Dieterich; in those patents are described methods and apparatus for producing photographic pictures having the effect of relief or depth.

One of the dominant aims of this invention is 10 to provide a method and apparatus of the above-mentioned character in which control of lens movements may be achieved in a more facile, more flexible, and more advantageous manner than has heretofore been proposed and in general 15 to improve upon the methods, apparatus, and results disclosed in the aforesaid Dieterich patents. Another object is to provide a lens mounting or mountings and a method and apparatus for moving the latter that will dependably avoid possible 20 deficiencies in known methods or apparatus for effecting lens movement. Another object is to provide a method and apparatus for controlling the movement of a lens or lenses that will be capable of precision and simplicity of control and 25 of wide range of flexibility.

Another object is to provide a dependable and 30 easily operable method and apparatus for testing or determining a setting or action of one or more movable lenses of a lens system. Another object is to provide, in a method and apparatus of the 35 type disclosed in the said Dieterich patents, a simple yet precise and accurate method and apparatus for determining and testing the range of movement to be given to a movable lens or lenses of a lens system and to test and determine the 40 action of such setting or movement.

Another object is to provide a lens system having one or more movable lenses capable of greater accuracy and speed of movement and greater flexibility of change in speed or range of movement 45 thereof than has heretofore been possible.

Another object is to improve in general upon known methods and apparatus for achieving, in photographic recording or reproduction of objects 50 or scenes, the effect of relief or depth. Another object is in general to provide an improved method and apparatus for achieving improved photography having the effect of relief or depth and more particularly to provide such improved method and apparatus that will be well adapted to 55 meet the varying conditions and requirements met with in practice, particularly in motion picture work, and to provide, particularly in the latter field, a wide range of accurate and dependable control and action, depending upon the various

and different conditions met with or effects that are desired to be achieved. Another object is to provide an apparatus of the above-mentioned character which will be compact, durable, easily mobile, and well adapted, particularly as to such 5 matters as ease and speed of adjustment, control, testing, or the like, to meet the peculiar and varied requirements of photography in general and motion picture photography in particular. Other objects will be in part obvious or in part 10 pointed out hereinafter.

The invention accordingly consists in the features of construction, combinations of elements, arrangements of parts, and in the several steps and relation and order of each of the same to one 15 or more of the others, all as will be illustratively described herein, and the scope of the application of which will be indicated in the following claims.

In the accompanying drawings in which are shown several illustrative embodiments of the 20 invention,

Figure 1 is a plan view on a small scale of a camera, illustratively a motion picture camera;

Figure 2 is a side elevation thereof;

Figure 3 is an end elevation as seen from the 25 right in Figure 1;

Figure 4 is a perspective view on a still smaller scale of such a motion picture camera illustrating also the manner in which certain of the control apparatus is associated therewith;

Figure 5 is a central vertical sectional view, with certain parts broken away or omitted, and on an enlarged scale, substantially as seen along the line 5—5 of Figure 1, or the line 5—5 of Figure 3, showing a preferred form of lens mounting and 30 actuating mechanism;

Figure 5^a is a detached view indicating a possible form of step-by-step film-advancing mechanism;

Figure 6 is an elevation, as it would be seen 40 along the line 6—6 of Figure 5, of part of the structure carrying the lens mounting and lens-moving means;

Figure 7 is an elevation of part of a magnetic field structure;

Figure 8 is an elevation as seen from the left of Figure 7;

Figure 9 is a plan view of a vibratable support for the lens mountings;

Figure 10 is an elevation illustrating a possible 50 modified form of a vibratable support for a lens mounting;

Figure 11 is a view on an enlarged scale, as seen from the right in Figure 2 or from the front of Figure 3, certain parts of the camera per se 55

being omitted and certain parts being shown in elevation and others in section to show the construction more clearly;

Figure 12 is an electrical diagram of the circuit arrangements and electrical system for achieving certain controlling and testing actions and operations;

Figure 13 is a central vertical sectional view, like that of Figure 5, with certain parts broken away or omitted, and on an enlarged scale, substantially as seen along the line 5—5 of Figure 1 or the line 5—5 of Figure 3, showing a preferred form of lens system with its mounting and actuating and related mechanism, and

Figure 14 is a diagrammatic representation, like that of Figure 12, of the circuit and other arrangements for effecting certain controlling, operating, and testing operations of the lens system of Figure 13.

Similar reference characters refer to similar parts throughout the several views in the drawings.

As conducive to a clearer understanding of certain features of this invention, it might here be noted that, while I have shown the illustrative embodiments of my invention and described them hereafter as particularly adapted for motion picture photography I do not intend to be limited to the latter and hence it is to be understood that my invention contemplates and includes still or like photography, as well as, generally, the production of images of any scene, object, or the like. Accordingly, and turning now first to Figures 1—4, I have there shown a camera of the motion picture type; it comprises a casing 30 mounted as later described upon a base or frame 31, the latter being mounted upon any suitable support diagrammatically indicated in Figure 4 at 32. The camera casing 30 is provided as shown in Figure 4 with suitable film reels or holders 33 and 34 for coaction with the film 35, the latter being in the usual strip form, and being fed through suitable film-driving mechanisms (not shown) including the usual shuttle mechanism, shutter, or the like, as is now well known in the art and examples of which may be found in Dieterich Patent 2,025,731. The camera casing 30 is provided with any suitable source of driving power, such as a hand crank, motor, or the like (not shown) to achieve the desired operation of the various film handling and coacting mechanisms, such as those above-mentioned. By way of illustration, however, I have shown in Figures 1, 2 and 4, as illustrative of such a source of driving power a hand crank 36.

In so far as the above-described parts are concerned, they may take any suitable or appropriate form and they may be like those embodied in well-known commercial forms of motion picture cameras. Preferably, the camera is so constructed, also as is well-known, as to have the casing 30 slidably transversely relative to the base 31, the latter having transverse ways 37, 38 for guiding the casing transversely. Also, the right-hand portion of the base 31, as seen in Figures 1, 2 and 4, has an upright hollow casing part or standard 40 with respect to which the casing 30 is likewise slidable.

Upon the front of the upright standard 40 (Figures 1 and 2) is rotatably mounted a disk-like plate 41 suitably provided with means for holding a suitable number of lenses or lens systems, illustratively four in number, as shown in Figure 3 at 42, 43, 44, 45, plate or lens support 41 being carried for rotary movement by a stud

shaft 46. The lenses or lens systems 42, 43, 44, 45 may thereby be selectively positioned with respect to the aperture, shutter and film of the camera and may be of any desired or suitable construction and preferably different action, excepting that at least one of them, illustratively the lens system 42, embodies certain features of my invention and hence in Figure 3 it is the lens system 42 that is shown positioned for having the film 35 exposed therethrough, the camera casing 30 being for such purposes shifted into the position shown in Figure 1. The casing 30, when shifted downwardly along ways 37, 38, to its other extreme position, permits the operator to sight through the selectively positioned lens system and to witness or inspect the scene or object which is about to be photographed. Casing 30 when given an intermediate position alines a casing extension 46 (Figures 1 and 3) with the optical axis of the selected lens system and likewise alines with the latter an aperture 47 (Figure 3) to permit the entry into the casing part 46 of light rays from the lens system, the casing part 46 containing certain light-sensitive testing devices as later described in detail.

Considering now more in detail the lens system 42, reference may first be made to Figure 5 in which the lens system 42 is shown in enlarged vertical central cross-section, being enclosed or encased, with certain related mechanism later described, in a cylindrical casing 50 carried in any suitable way by the lens-carrying plate 41, to which also the lens system and related parts are preferably secured in any suitable way. In Figure 5 the rotatable plate 41 is shown only fragmentarily and it is, of course, provided with a suitable opening to which is related in any suitable way a separate aperture member 51 adjacent to which is mounted a suitable shutter diagrammatically indicated at 52 to control the exposure through the lens system and through the aperture 51 of the film 35, the latter being indicated diagrammatically in Figure 5. Any suitable means may be employed to advance the film to present frames thereof successively into the image plane for successive exposure by the shutter and it may take the form of that shown in Figure 2 of Dieterich Patent No. 2,025,731, the pertinent parts of which are reproduced in Figure 5a herein. In the latter a portion of the film 35 is shown in relation to the apertured shutter 52, the latter being driven in any suitable way as by the shaft 52^a, comprising a suitable member to engage in the holes in the strip film for moving the latter, periodic movement being achieved in any suitable way as by a cam 52^c on the shaft 52^a having suitable connections indicated at 52^e with the film-engaging member 52^b.

The lens system 42, according to one embodiment thereof, may comprise lenses 53, 54 and 55 constructed individually in any suitable way and preferably and illustratively constructed to constitute a lens system of the type shown in Figures 2, 3 and 4 of Dieterich Patent No. 1,927,925; thus, lens 53 may correspond to lens 20 of the patent, lens 54 may correspond to lens 21 of the patent, and lens 55, though shown in Figure 5 as a single lens, may comprise the composite lens 22—23 of the said Dieterich patent; these three lenses or lens groups are to be given certain movements relative to each other and relative to the image or film plane represented diagrammatically by the film or sensitized camera element 35 in Figure 5, and for a detailed explanation of the construction of this lens system

and of the above-mentioned relative movements, reference is to be had to the said Dieterich Patent No. 1,927,925. In the latter are described various ways in which such a lens system may be actuated to achieve upon the sensitized camera element or film an infinite number of images of the scene or object, each, however, corresponding to a different focus or plane of sharpness and all of the recorded images being of the same size and registering throughout, thereby giving the recorded effect of relief or depth in the scene or object photographed.

Where the lens system is of the just described Dieterich type, I prefer to provide separate and 15 separately movable mountings for the individual lenses or lens groups and also separate moving means for these mountings; since in general these mountings and moving means are substantially the same for each lens or lens group, one 20 of them will be described in detail and the others described only generally.

Thus, considering the lens 53 of Figure 5, it is supported in any suitable way, as by threaded clamping rings (not shown) in a cylindrical carrier 56, the latter being preferably of brass and having its axis coincident with the optical axis of the lens 53. The lens carrier 56 is secured to a diaphragm-like spring support 57, in any suitable manner, which is disk-like in shape, 30 made of a suitable spring material, preferably metallic and preferably non-magnetic. Illustratively, it may be made of sheet spring bronze, and in form and shape it may take that better shown in Figure 9; by way of further illustration, 35 it may be made of non-metallic material, such as Bakelite in sheet form, preferably with a cloth base.

Referring now to Figure 9, the spring lens support 57 will be seen to be in the form of a disk 40 of substantial diameter, having a central round opening 58 to the periphery of which the lens mounting 56 (see Figure 5) may be mounted or secured in any suitable manner, as is illustrated in Figure 5.

45 About the opening 58 (Figure 9) the spring mounting preferably has a substantial ring-like area or unbroken portion 59 to which is secured, as by screw or the like, an annular or ring-shaped armature 60 (Figure 5) of a suitable 50 magnetic material, such, for example, as permalloy. Preferably, the armature 60 is physically and magnetically held in spaced relation from the portion 59 of the spring mounting 57, by an interposed ring or collar 61 made of brass.

55 The non-magnetic collar 61 and the armature 60 are preferably secured together coaxially as by rivets (not shown) and the resultant unit mounted on the mounting 57 so that its axis is coincident with the optical axis of lens 53. This 60 mounting may be achieved in any suitable manner, illustratively as by screws 63 (Figure 9) at appropriately spaced points threaded into the armature and by rivets 62 preferably alternated with the screws 63. By way of loosening the 65 screws 63 in course of assembly the armature may be allowed to find its magnetic alignment and may then be anchored in position by the rivets 62 as well as screws 63.

70 The armature 60 carries an energizing coil 64 wound and terminated in any suitable manner and in a like way is supported upon and insulated from the outer cylindrical periphery of the armature 60, the latter being preferably peripherally grooved to receive the winding 64.

Winding 64 and armature 60 are made to coat with certain parts later described in detail.

Referring again to Figure 9, the disk-like lens support 57 has an outer substantially unbroken or ring-like portion 65 which is joined to the inner ring portion 59 by a suitable number of uniformly distributed arms 66, this configuration of the sheet-like support 57 being achieved, for example, by stamping or punching operations, which cut out openings 67 in the disk to provide these yieldable or spring-connecting arms 66. The outer ring portion 65 of the lens support 57 is provided with suitably and uniformly spaced holes 68 whereby, and with other parts later described, the outer ring portion 65 may be securely anchored against movement so that the inner ring portion 59, with its armature 60 and coil 64, may move axially because of the springiness of the material of the member 57 and particularly because of the springiness of the connecting arms 66.

The latter, moreover, when shaped as shown in Figure 9, provide virtually three axes about which the arms or portions thereof may bend relative to each other, and in Figure 9 these axes 25 are shown, with respect to one of these connecting arms at A—A, B—B and C—C. Thereby the arms 66 insure a nice resiliency or yieldability of mounting of the armature 60 and of the lens mount 56 (Figure 6) and the uniformity of distribution, construction, and action of the arms 66 insure that any movement of the lens 53 is always a true axial movement and that the lens 53, as it moves axially, does not partake of any tilt with respect to the optical axis of the lens 35 system with which its own optical axis is coincident and must, therefore, remain coincident throughout movement.

In Figure 10 is shown and indicated by the reference character 57^a another possible form 40 or shape which the spring lens support 57 just described may assume; here there are again provided inner and outer annular or ring-shaped portions shown at 59^a and 65^a and by providing uniformly distributed curved slots 70—71, 70—71, 45 etc., the central ring portion 59^a with the armature 60 and lens mount 56 becomes supported by composite or bifurcated arms 72 which, in yielding, may bend about axes F—F, G—G and H—H. Here again, the spring disk-like support 50 may be easily fabricated as by stamping.

Recurring to Figure 5, the outer ring portion 65 of the spring support 57 is seated against the annular face of a recess 73 in a relatively heavy annular or ring member 74 made preferably of 55 a suitable non-magnetic material like brass and it is clamped and thus securely anchored against this annular face 73 by a clamping ring 76 also preferably made of non-magnetic material such as brass. The non-magnetic ring member 74 is cut away as at 77 throughout its side face so as to clear the free or unrestrained portions of the spring support 57 and to give such portions freedom of vibrating or oscillating movement as the connecting arms above-mentioned in connection with Figures 9 and 10 are made to yield, and within the circle of largest diameter of this cut away portion 77, the ring member 74 is shaped or cut out rectangularly to form a rectangular seat 78 shown in Figure 6. Seat 78 has fitted into 65 it and secured thereto in any suitable way a field structure made of magnetic material, such as permalloy and shaped as is better shown in Figures 7, 8 and 5.

This field structure comprises a part 80 and a 75

companion part 81 (Figure 5). Part 80 has an upstanding main portion 82 (Figures 5, 7 and 8) that is rectangular in shape and thus receivable within the above-mentioned seat 78 (Figures 6 and 5) and at its upper and lower ends has horizontal extensions 83, 84 from which extend, in a direction parallel to the main portion 82, portions 85 and 86, respectively; the latter portions fall short of meeting each other (see Figure 8) and, furthermore, have their juxtaposed faces arcuate in shape, as at 87 and 88, respectively (Figures 7 and 8), the radius of curvature of these juxtaposed faces 87, 88 being somewhat greater than the radius of the outer cylindrical face of the armature 60 (see Figure 5). The main portion 82 of the member 80 has a central round aperture 90 therein.

In this aperture 90 is fitted and secured in any suitable way the above-mentioned companion field piece 81 (see Figure 5), the latter being annular or ring-shaped and rabbeted to interfit with the apertured main portion 82 of the member 80, as shown in Figure 5.

The largest or outside diameter of the field piece 81 is less than the inside diameter of the ring-shaped armature 60 and thus forms with the arcuate pole faces 87-88 (Figures 7 and 8) a substantially annular air gap into which, as shown in Figure 9, the armature 60 extends and is received. The inside diameter of field piece 81 is somewhat larger than the outside diameter of the lens mounting 56 (see Figure 5) and thus there is provided appropriate clearance for the axial movement of the lens mounting 56.

To set up a magnetic field across the air gaps of the core or field structure 80-81, I provide a winding 91 (Figure 5) of annular form and extending about the field part 81; this winding when energized sets up a magnetic field or flux whose circuit (or circuits) includes the core structure 80-81 and the air gaps in which extends the armature 60. Preferably, the field winding 91 is energized with direct current of a given value and hence there extends across the air gaps a magnetic field or flux of a corresponding value, that flux being, like the current producing it, uni-directional, and in such case I energize the armature winding 64 by an alternating current of appropriate frequency, thereby producing a magnetic field or flux which, like the current producing it, is also alternating. Accordingly, with every reversal in the current in and hence flux produced by the armature winding 64, change in direction of movement of the armature and hence of the lens 53 takes place, and the extent or range of movement of the lens 53 being a function of the strengths of the respective magnetic fluxes, and a function of the yieldability of the spring-supporting member 57. By increasing or decreasing either or both of the energizing currents, a corresponding change in amplitude of oscillation or movement of the lens 53 is brought about, and by appropriately selecting or changing the frequency of the alternating current employed, the rate of oscillation of the lens 53 may be determined as is desired.

The remaining lenses of the lens system of Figure 5 are mounted and moved in a substantially similar way. Thus, lens 54 is carried in a lens mount 92 supported by a spring support 93, the latter carrying the armature 94 by way of the spacer ring or collar 95 and being seated in a recess 96 in a ring member 97 and held thereagainst by a clamping ring 98. The non-magnetic ring member 97 has a substantially rectan-

gular opening 100 in it to receive the field or core structure 101-102, the latter having an energizing winding 103, illustratively energized by direct current, and the armature 94 having a winding 104 illustratively energized by alternating current. These various parts are similar in construction to those earlier above described in connection with lens 53 and the resultant two unit assemblies, carried by the ring members 74 and 97, respectively, are assembled to each other, as by placing them face to face, as shown in Figure 5, thereby bringing the two clamping rings 76 and 9 into engagement with each other and also the frame ring members 74 and 97. The parts are secured together in any suitable way as by screws, bolts, or the like, and the parts are also so proportioned and shaped that the optical axis of the lens 54 is coincident with that of the lens system as a whole and also so that the lens 54 moves lengthwise of that optical axis and without tilting.

In like manner a mounting for the lens or lens group 55 is provided, the latter being carried in a mount 105 carried by the spring support 106 seated in a recess 107 of a ring frame member 108 generally similar to the ring members already described; the spring support 106 has mounted on it an armature 110, by way of the non-magnetic ring or spacer 111, and armature 110 has a winding 112, illustratively thereby energized by alternating current.

The frame ring member 108 has a substantially rectangular recess 113 in which is received the two-part core structure 114-115, the latter being provided with a winding 116 to be energized illustratively with direct current. Spring support 106 is clamped in place by a clamping ring 117 and the resultant lens mounting and moving unit is secured to the preceding unit, back to back, in any suitable way as by screws or bolts (not shown). Here again, the parts are so shaped and dimensioned that the lens 55 has its optical axis coincident with the optical axis of the lens system and so that it moves along that optical axis without tilting.

In each case, also, and preferably, the effective magnetic axis of the electromagnetic means is coincident with the optical axis of its lens or lens group and hence with the optical axis of the lens system.

The resultant lens system, with its components individually movable, may now be operated, during exposure of the sensitized camera element, in accordance with the theory and explanation contained in the said Dieterich Patent 1,927,925 with respect to its Figures 2, 3 and 4, and in carrying out such operation in accordance with certain features of my invention, I may and preferably do energize the three field windings 91, 103 and 116 with direct current, and energize the armature windings 64, 104 and 112 with an alternating current, so determining the directions of their respective fields, however, as to cause lenses or lens groups 53 and 55 to move in substantial synchronism and to cause lens or lens group 54 to have its movements out of phase with the synchronous movements of the lenses 53 and 55.

Where the assemblages of lenses 53 and 55 are mechanically the same and the assemblage of lens 54 is mechanically reversed with respect to them, the above described out-of-phase movement of lens 54 may be achieved by energizing 2/3 of the armature windings 64, 104 and 112 electrically in phase or in the same direction and

by connecting the field windings 91, 103 and 116 in parallel, and in such a way that their respective fluxes pass or act in the same direction relative to their respective armatures. Were the assemblage of lens 54 not mechanically reversed relative to the others, the out-of-phase movement is achieved by reversing the connections of one of the windings of the assemblage of lens 54. Accordingly, one half cycle, lenses 53 and 55 move, say to the left and substantially as a unit, while lens 54 moves to the right, and during the next half cycle of the alternating current, these lenses move in respectively reversed directions.

Therefore, change in focus and hence change in the position of the plane of sharpness through the scene is effected but accompanied by maintenance of the size of the in-focus and out-of-focus images on the sensitized camera element 35, the movement of lens 54 being such as to rectify the change in size of images caused by the shifting of lenses 53 and 55. During alternate half cycles, therefore, successive and relative shifts in the three lens groups 53, 54 and 55 take place as are shown diagrammatically in Figures 2, 3 and 4 of the said Dieterich patent, relative shifts in relatively reversed directions taking place during intervening cycles. The manner of control, adjustment, or regulation, of the lenses or lens groups of Figure 5 and of their movements are carried on as is later described in detail.

Considering further the structural arrangements shown in Figure 5, it is to be noted that the resultant unitary assembly of the several sub-units is secured in any suitable manner to the rotatable lens-carrying plate 41 (see also Figures 1-3) and preferably enclosed also in the casing 50, and where it is desired to vary the amount of light with change in focus, as taught in the said Dieterich patent, I prefer to employ a variable aperture or diaphragm comprising four plate members 120, 121, 122 and 123 (see now Figure 11), shiftable to vary the size of the rectangular opening formed thereby and through which light rays from the scene or object to be photographed pass on their way to the lens system of Figure 5. These plate members, arranged in opposed pairs, as shown in Figure 11, are carried by a disk-like mounting plate 124 which, as shown in Figure 5, is interfit with the right-hand end of the assembly unit of lens 55, being secured thereto in any suitable way as by screws, or the like, and preferably also abutting against the clamping ring 117.

This supporting plate 124 has an aperture aligned with the optical axis of the lens system and if desired may have related to it an iris diaphragm for fixing the base value of light from the scene or object and with respect to which base value of light variations are to be achieved during the changes in focus.

Accordingly, the mounting plate 124 is recessed as at 125 (Figure 5) and in that recess is mounted any suitable or known form of iris diaphragm 126 provided with any suitable means, indicated at 127, for adjusting or setting it. And to the right of the iris diaphragm 126 are positioned the light-varying plate members 120, 121, 122 and 123. The latter are movably mounted, as is later described in detail, on the front of the plate 124 so that opposed pairs of these plates may be moved toward or away from each other (Figure 11). To each plate member is related and connected a plate-moving and controlling means or unit, as indicated at 130, 131, 132 and 133, and inasmuch as these four units are of identical

construction, it will suffice to describe only one of them in detail.

Accordingly, and still referring to Figure 11, the unit 130 comprises a two-part rectangular frame 141 and 142 secured together as by screws 143 but having clamped therebetween two opposed end portions of a sheet material spring support 144, preferably corrugated and which is to function substantially like members 47 of Figures 9 and 10. The rectangular spring support 144 carries a small ring-shaped or annular armature 145 provided with a coil 146 and the armature 145 projects into air gaps formed in and by a two-part field or core structure 147 and 148. Field or core part 147 is constructed and shaped substantially like the part 80 of Figures 7 and 8 and is made of a magnetic material like Permalloy, being fitted in between, and secured by screws 150 to, opposed downwardly directed extensions 142a of the non-magnetic frame part 142. The core part 147 has extending upwardly from its bottom portion the hollow ring-shaped core part 148, the latter being in general like the core part 81, for example, of Figure 5, and about the core part 148 is a winding 151 which is energized by direct current in which the armature winding 146 is energized by alternating current.

The frame parts 141-142 are supported for sliding movement in suitable ways 152 provided on or in the plate member 124 and the latter has a lug or projecting portion 153 through which is threaded the thumb screw 154, the latter being provided preferably with micrometer type of calibrations to facilitate speed and accuracy of setting. The lower end of the thumb screw is in 35 rotatable connection with a cross-piece 155 bridged across the frame part 141 and accordingly, when the thumb screw 154 is manually rotated, the frame 141-142 with the parts carried thereby is correspondingly moved up or down, 40 as viewed in Figure 11, along the guiding ways 152, suitable springs 156 being provided to take up any lost motion or back lash.

Such movement of adjustment is transmitted to the diaphragm plate 120 by a connecting link 157 whose upper end is anchored as by a screw 158 to the exact center of the spring support 144.

But the corrugated spring support 144 may and does partake of movement under the coaction of the two windings 146 and 151 and their coacting 50 magnetic circuits or parts and the movements of the spring support 144, communicated to the diaphragm plate 120, may be coordinated in any desired way with the movement of the lens system or any component part of the latter, all as will be 55 later described in detail.

The control units 131, 132 and 133 (Figure 11) of the diaphragm plates 121, 122 and 123, respectively, are, as above-mentioned, of identical construction as is also shown in Figure 11, as to 60 which it need at this point only be noted that the respective field and armature windings thereof are indicated by the reference characters 161, 162 and 163 for the field windings and 164, 165 and 166 for the armature windings. The various field 65 windings and armature windings may be connected in parallel or series; after initially setting or determining (as by the thumbscrews 154) the average or mean size of aperture formed by the four diaphragm plates, the latter are moved 70 toward or away from each other synchronously, the amount of light passed therethrough correspondingly varied, and suitably coordinated with changes in focal length brought about by the lens system as above described.

- In the casing part 46 (Figures 1 and 3) and exposed to the aperture 47 (Figure 3) is mounted a photoelectric cell 170 and the latter and associated circuit and control and indicating means 5 I preferably arrange to facilitate an initial setting or testing of the action of the lens system and related parts above described. Due to the arrangement, illustratively as by sliding the camera casing 30 along its ways 37, 38, as already 10 above described, the sensitized camera element 35 can be moved out of juxtaposition to the lens system and the photoelectric cell 170 substituted for it, for purposes later described in detail.
- The above described electromagnetic and electrical parts or features of my invention are electrically interrelated by circuit arrangements of which Figure 12 depicts an illustrative embodiment; in Figure 12 the various windings coacting to effect movement of the various lenses and 20 diaphragm parts are diagrammatically indicated and identified by their respective reference characters. Preferably I utilize a suitable source 171 of alternating current, for example such as is commercially available, usually of 60-cycles and 25 110-volts. For reasons later set forth I prefer to provide also appropriate means for varying or changing the frequency and at 172 I have diagrammatically indicated what I shall term a frequency changer. This may comprise any suitable means or apparatus such as, for example, a motor-driven alternator, the speed of drive and hence the frequency of output of which may be varied or changed throughout a suitable range. From the frequency changer 172 conductors 173 30 and 174 lead through a suitable voltage-regulator 175 to a step-down transformer 176; the output of the transformer 176 is passed through a filter 177 and from thence conductors lead to the armature coils 64, 104 and 112, connecting the 40 latter in parallel so as to permit the insertion of their respective branch circuits of current-varying or control devices, illustratively in the form of rheostats 178, 179 and 180, respectively, and of indicating meters, preferably volt meters, 181, 45 182 and 183, respectively. Thereby the armature windings may be independently energized and their respective energizations determined or varied as circumstances require, and also visually indicated by the meters.
- 50 The field windings 91, 103 and 116, of the various lens units, are supplied, as above noted, with direct current. By way of conductors 184 and 185, alternating current energy from the source 171 is supplied to a rectifier diagrammatically indicated at 186; this rectifier may be of any suitable type, is preferably a full wave rectifier, and preferably, also, includes means, such as an input stepdown transformer, for reducing the voltage of the direct current output of the 55 rectifier.
- Suitable conductors connect the field windings 91, 103 and 116 to the direct current output of the rectifier 186 and illustratively they are connected in series through a current-controlling device, such as a rheostat 187, and also through an indicating device or meter 188, such as an ammeter for indicating the energization of these 60 windings.
- Suitable switches 189 and 190 may be provided to open or close the circuits of the respective field and armature windings. In analogous manner the field windings 151, 161, 162 and 163 65 of the light-controlling devices of Figure 11 are connected in series and to the direct current source, such as the output of the rectifier 186;

preferably a suitable current-varying or controlling device, such as a rheostat 191 and a switch 192 are provided in this circuit. Likewise, also, the armature windings 146, 164, 165 and 166 of the light-controlling means of Figure 11 are connected in parallel, as indicated, and supplied with low voltage, from the circuit 173-174, by means of a transformer 193 in whose primary circuit is included a suitable voltage regulator 194 and a switch 195 and in whose secondary circuit is included a suitable current-varying device such as a variable resistance 196.

Accordingly, with all of the circuits closed and appropriately adjusted, the various lenses or lens groups, such as the lenses 53, 54 and 55, are set 15 into movement or oscillation at a frequency or periodicity which is a function of the frequency of the alternating current energizing the armature windings, and as set forth above lenses or lens groups 53 and 55 move in synchronism and 20 in the same direction but lens or lens group 54, while moving synchronously with the other lenses, moves in opposite direction with respect to the latter, for reasons already set forth above.

The diaphragm plates 120, 121, 122 and 123, move in synchronism, opposite or opposed plates moving toward each other at the same time during one half cycle and away from each other during the succeeding half cycle, thereby restricting and enlarging the aperture, and doing so synchronously with the movements of the lenses of the lens system inasmuch as their armature windings 146, 164, 165 and 166 (Figure 12) are energized in phase by the same frequency of 35 alternating current energy as are the armature windings of the lens system.

As for the photoelectric cell 170, that is shown diagrammatically in Figure 12 and its electrodes are included in a circuit in which is included a 40 suitable source of potential 200 which is preferably derived, as by conductors 201 and 202, through a switch 203 from the principal or primary source 171, the above-mentioned source 200 comprising any suitable device, well known in the art, for providing in the circuit of the photoelectric tube 170 a suitable potential. In the output circuit of the tube 170 is included a suitable measuring or indicating device 204 that is preferably of a sensitive and precision type, such as a vacuum tube type of A. C. voltmeter, for indicating current flow in the circuit of the photoelectric cell and also variations in such flow; this indicating means may, if desired, include an amplifier 205, and preferably the circuit of the 55 light sensitive cell 170 has associated with it also an electrical filter 206.

The various control and indicating devices and circuits, excepting for the field and armature windings, the photoelectric cell, and its amplifier, 60 may be assembled and compacted in a portable casing 207, as indicated in Figure 4, suitable cables 208 and 209 leading certain of the circuits to the field and armature windings and to the photoelectric cell and its amplifier and a suitable cable 210 leading other conductors to, for example, a connector plug 211 by which connection may be made to a suitable source of primary energy, such as the source 171 of Figure 12. Preferably, the amplifier 205 is mounted in the casing part 46 that contains the photoelectric cell.

The various manually operable parts of the circuit arrangement of Figure 12, such as rheostats, switches, or the like, may be exposed from the cabinet 207 (Figure 4) in any suitable man-

ner for convenient manual operation, and the various indicating devices or meters may likewise be so related to the cabinet 207 as to be readily observable by the operator, all as is diagrammatically or fragmentarily indicated in Figure 4. Thus, the control equipment and accessories can be conveniently associated with the camera itself and meet such requirements of the latter as mobility, portability, or the like.

10 After having closed the various circuits to make them effective, thus setting the lens or lenses and the light-controlling means of Figure 11 (where the latter is desired to be employed) into movement or oscillation, the camera casing 30 is shifted to bring the aperture 47 (Figure 3) and hence the light-sensitive cell 170 in alignment with the optical axis of the system, whereupon a current flow becomes effective in the circuit of the cell 170 and a corresponding potential is indicated by the voltmeter indicator 204 (Figure 12). To achieve the desired setting or range of movement of the movable lens or lenses for a given condition of light on the scene or object to be photographed, the movement of the light-controlling means of Figure 11 is first halted, as by opening the switch 195 of Figure 12, and the iris diaphragm 126 set or adjusted to determine the means or average value of light that is to pass through the lens system suitable for or appropriate to the particular character of the scene itself.

If the amplitude or distance of travel of each of the synchronously moving lenses or lens groups is not properly correlated with respect to the amplitude or travel of the other lens or lens groups, the images projected upon the photoelectric cell will in effect be blurred, in that out-of-focus images do not register concentrically with in-focus images and thus the effective light transmitted to the photo cell 170 is in quantity different from the light which would reach it if the in-focus and out-of-focus images were of the same size and hence registered, as would be the case if the movements of the lenses relative to each other or to the film plane (in which the light-sensitive element of the photo cell 170 finds itself) were properly correlated. Accordingly, the indicator 204 (Figure 12) gives an indication of this inappropriate condition and since the movement of the lens or lenses is periodic, the indicator 204 also registers the fluctuating light density in terms of alternating current, the electrical filter 206 being switched into its circuit by its switch 260 during these operations and acting as is later described in greater detail.

Accordingly, after again closing switch 195 suitable adjustments are made of the respective currents flowing to the armature windings 64, 104 and 112, by manipulating their respective rheostats 178, 179 and 180, all with respect to a given or initial suitable setting of the variable resistance 187 that determines the current flow to the field windings.

These adjustments are made in directions that are perceptible from watching the corresponding change or direction of change of the indicator 204.

Interference with the action of the testing system and with the indication of the indicator 204 by foreign or outside fluctuations is negated by the action of the regulator 175, the latter being preferably of the core-saturation type, in negating fluctuations in the source 171, and by the filter 177 which is adjusted to suppress all frequencies other than that with which the arma-

ture windings are energized, illustratively a frequency of 60 cycles; but also taking part in these actions is the filter 206 which is connected in parallel by switch 260 in the output circuit of the photoelectric cell amplifier and which is so proportioned or adjusted as to suppress all frequencies other than the frequency of the current in synchronism with which the armatures and their respective lenses are vibrating or oscillating. Thereby, also, oscillations or variations in the normal light reaching the image of film plane, and corresponding to the "noise level" or frequency of the normal light, are suppressed and prevented from causing the indicator 204 to give false indications. Accordingly, the indicator 204 is made to give a true indication of the light action of the lens system, foreign disturbances or frequencies being thus dependably eliminated.

As soon, therefore, as such adjustments have been made of the currents energizing the armature windings, one with respect to the other, as cause the indicator 204 to reach a minimum or near-zero reading, the lens system will have been adjusted properly, both as to the individual ranges of movement of the individual lenses and as to the relative movements between the lenses, the steady or minimum indication of the indicator 204 indicating that the in-focus and out-of-focus images of the scene or object are in the image plane, of the same size and in registry with one another, a condition which corresponds to substantially no variation in light intensity. Or, in any case, the adjustments are made so as to achieve a minimum, if not an absolute zero, indication or fluctuation of the indicator 204 to correspond to substantial coincidence of in-focus and out-of-focus images in the image plane.

The resultant action of the lens system is one corresponding to that described in Dieterich Patent 1,927,925 with respect to Figures 2, 3 and 4 thereof.

In practicing the art of photography, scenes of different depths are, of course, met with. For example, an indoor scene generally is of less depth or distance from the foreground to the background than is an outdoor scene that includes or sweeps a substantial range of terrain. By way of my system I may quickly and easily set the range of movement of the lens or lenses so that the range of change of focus corresponds very closely to the depth of the particular scene to be photographed. For example, if the scene is of small depth, such as an indoor scene, the energization of the armature windings of lenses 53 and 55 (Figure 5) is first so adjusted that the range of change of focus of the lens system is such that the plane of sharpness moves from a point near the camera to a point (or plane) corresponding substantially to the background or wall of the scene and thereafter the energization of the armature winding of lens 54 is adjusted or set, in the manner above described and with reference to the indicator 204, to bring the in-focus and out-of-focus images to the same size and in registry with each other.

If the scene is one of very great depth, such as an outdoor scene that includes a remote landscape, for example, then the energization of armature windings of lenses 53 and 55 is so set that the plane of sharpness of the lens system moves from a point or plane near the camera to a point or plane as remote as the remotest point in the scene, and then the energization of

armature winding of lens 54 is set, in the manner above described, again to bring the in-focus and out-of-focus images to the same size and in registry with each other.

5 Thus, the lens system can be quickly and with precision suited to any particular range of change of focus called for by the depth of the particular scene or object to be photographed. Thereby the maximum efficiency of the lens system is brought 10 to bear during each exposure and superior light action on the film or sensitized camera element achieved.

If desired, the control apparatus, such as that shown in Figure 12, may be calibrated with respect to each of the adjusting devices, such as the various rheostats or variable resistances, and also with respect to the various indicators or meters. For example, the voltmeters 181, 182 and 183 (Figure 12) may be calibrated both in volts 20 and in focal distances or depths of scene for given indications of the ammeter 188 in the circuit of the field windings; if this is done, then corresponding rheostats 178, 179, 180 and 187 may be at least preliminarily set to give the desired 25 indications of the voltmeters and ammeter in terms of focal distances or depth of scene, and the photoelectric cell arrangement above described utilized as a final or precision checking of the adjustments thus given.

30 With the lens movements properly set or determined, the light-varying or controlling means, such as the diaphragm plates 120, 121, 122 and 123 of Figures 5 and 11, may be set into action as by closing switches 195 and 192 (Figure 12) and 35 rheostats 191 and 196 adjusted to give the desired range of change of light during each exposure; when these diaphragm plates are thus set into action they move in synchronism with the movable lens or lenses of the lens system for all of 40 the armature windings are energized by the same frequency of alternating current. The resultant variations in light upon the photoelectric cell 170 are in the nature of fluctuations of a frequency corresponding to the energizing alternating current employed and the indicator 204 in the circuit of the photoelectric cell 170 may be used (it may also be correspondingly calibrated) to determine the respective settings of the variable resistances 191 and 196 and thereby to determine 45 with precision the range of change of light intensity from the average value set by the iris diaphragm 126. Here again, a suitable indicating device 220, illustratively taking the form of an ammeter, and an indicating device 221, illustratively taking the form of a voltmeter, may 50 be used (and also calibrated in terms of light variation, etc.) to indicate the settings of the energization of the field windings 151, 161, 162, 163 and of the armature windings 146, 164, 165 and 166, respectively.

55 Though the light-varying diaphragm plates move in synchronism with the movable lens or lenses, the armature windings of the former are preferably energized with alternating current in such a direction that the diaphragm plates progressively open as the lens system moves the plane of sharpness from a point near the camera to a point remote from the camera.

If desired, the results of the settings thus 60 achieved may be visually checked or such visual checking may be achieved during the procedure of setting and testing by shifting the camera casing 30 (Figures 1 and 2) to such a position that neither the film nor the photoelectric cell 75 170 is juxtaposed to the lens system but that the

latter is accessible from its rear to permit the operator to sight therethrough and see with the naked eye what the action of the system is.

In Figures 13 and 14 I have shown a modified form of lens system and operating control therefor in which the lens system per se takes the form of that described in Dieterich Patent 1,927,925 with respect to Figures 9, 10, 11 and 12 or of those described in Dieterich Patent 2,025,731. Thus, for example, in Figure 13 herein lenses 230, 10 231, 232 and 233 may correspond, respectively, in construction and action, to lenses 26, 27, 28 and 29 of Figures 2 and 5 of Dieterich Patent 2,025,731, or to lenses 226, 227, 228 and 229 of Figure 9 of the said Dieterich patent, or to lenses 4, 3, 2 and 1 of Figure 9-12 of Dieterich Patent 1,927,925; accordingly, reference to the said patents may be made for details of the construction and action thereof, and hence those matters need not be dealt with in detail herein. 20

Accordingly, and again referring to Figure 13 herein, which may be considered to be a sectional view as along the line 5-5 of Figures 1 and 3 herein, where it is desired to embody in the camera this modified and preferred embodiment 25 of my invention, the lens system will again be seen to be mounted on the lens-carrying plate 41, the latter being shown in Figure 13 in such a position that the lens system and related parts are shown juxtaposed to the diagrammatically indicated film or sensitized photographic element 35, the shutter 52 and the aperture 51, all as was described in connection with Figure 5. Where the film 35 is a motion picture film, its intermittent or step-by-step movement to present successive frames for exposure may be achieved by any suitable mechanism such, for example, as that described above in connection with Figure 5a. Where in Figure 5 the lens system as a whole was arranged to be moved and 40 one of the lenses moved relative thereto, in the arrangement of Figure 13, as in the said Dieterich patents just mentioned, lenses 230, 232 and 233 are stationary and lens 231 is movable. Lenses 232 and 233 may be mounted in any suitable manner (see Figure 9 of Dieterich Patent 2,025,731), in a sleeve-like extension 234 of a stationary mounting plate 235 adapted to rest against and be secured to the rotatable lens plate 41. 45

The movable lens 231 is mounted for movement and provided with a moving means therefor substantially identical with the mountings and moving means of any one of the lenses as described in connection with Figure 5, for example like those of lens 53 of that figure. The construction and action of the detailed parts therefore need not be described again, but it might be pointed out that the movable lens 231 is carried in a sleeve-like member 236 in turn secured to the sheet-like flexible or resilient or spring support 237, the latter carries a ring-shaped armature 238 secured thereto and spaced therefrom by a non-magnetic spacer ring 239. Armature 238 carries an energizing winding 240 and with the armature 238 is positioned in the annular-like 65 air gap between the field core structure 241-242, the latter corresponding, for example, to the parts 80 and 81, respectively, of Figure 5. The field core structure is energized by a field winding 243 preferably to produce a uni-directional magnetic 70 flux in the air gap, armature winding 240 being energized by alternating current of appropriate frequency.

The field core structure is carried in a ring-shaped member 244 secured in any suitable man- 75

ner to the lens supporting plate 235 and it has an annular or stepped recess 245 in which is seated the outer peripheral portion of the spring support 237, the latter being clamped in the said recess 245 by a clamping ring 246 held and pressed toward the ring support 244 in any suitable manner.

With this mounting of the movable lens 231 and energization of the armature and field windings in the manner above-described in connection with Figure 5, the lens 231 may be vibrated or oscillated at the frequency of the alternating current energizing the armature winding 240; such movement of the lens 231 is, of course, relative to the stationary lenses 232 and 233 and also to lens 230, the latter being suitably secured in a sleeve-like mounting 247 carried by or suitably secured to a disk-like mounting or supporting member 248 which rests against the clamping ring 246 and against the ring support 244, being secured to the latter in any suitable way. Of course, all of these lens supports and mountings are so shaped and assembled together and held so assembled that the optical axes of the individual lenses are coincident and hence coincide with the optical axis of the lens system. For reasons fully explained in connection with Figure 5, the movement of the movable lens 231 is such that the lens does not tilt and hence maintains its own optical axis always in coincidence with the optical axis of the lens system, throughout its range of movement.

Fitted up against the lens mounting or supporting member 248 is a frame ring 250 shaped at its left-hand face to mate with the supporting member 248, broadly in a manner similar to the way in which the mounting plate 124 (Figure 5) is aligned with and related to the ring support 108; the mounting plate 250 of Figure 13 is otherwise similar in construction to mounting plate 124 of Figure 5, having, therefore, an iris diaphragm 126 with a suitable manual control 127 and likewise having the movable plate members 120, 121, 122 and 123 with their associated moving and control means, all as described above in connection with Figures 5 and 11 and 12, these parts being therefore indicated, without further description, in Figures 13 and 14 by similar reference characters.

The lens system of Figure 13 and related parts may be related to or enclosed in a suitable casing 50 similar in general to the casing 50 of Figure 5.

In Figure 14 is shown diagrammatically the circuit arrangement preferably employed in operating the preferred embodiment of my invention, namely, that of Figure 13, and since many of the parts of Figure 12 are duplicated in Figure 14 and identified by the same reference character, the arrangement will in general be clear in view of what has been set forth in connection with Figure 12. It will be noted that the system is substantially the same as that of Figure 12 excepting that, since it is possible by way of the arrangement of Figure 13, to employ only a single movable lens, Figure 14 shows only a single field winding 243 to be energized from the direct current source and a single alternating current armature winding 240 to be energized from the source of alternating current, instead of three field windings and three armature windings, as in Figure 12. The adjusting and testing means of Figure 14 are the same as those employed in Figure 12.

If the movable lens 231 of Figure 13 is vibrated

or oscillated throughout an appropriate range and relative to the remaining lenses, all as described in the aforesaid Dieterich patents, as above-mentioned, the plane of sharpness is shifted back and forth from a point near the lens 5 to a point remote from the lens while at the same time in-focus and out-of-focus images are maintained at the same size and in registry, in accordance with the said Dieterich patents.

In setting the system, switches 195 and 192 10 are first opened so that the light-controlling or varying diaphragm plates 120, 121, etc. are motionless, and iris diaphragm 126 is set by its control 127 to determine the mean or average aperture through which light is to be allowed to pass 15 to the lens system from the scene or object to be photographed, the diaphragm plate moving units (see Figure 11) being set as by the adjusting screws 154 to give an average size of aperture commensurate with the aperture set or determined by the iris diaphragm 126. The procedure thus far is similar to that pursued in connection with the arrangement of Figure 5.

Next, the camera casing 30 of Figures 1, 2 and 3 is shifted so as to bring the photoelectric cell 25 170 in juxtaposition to the lens system and hence on the optical axis of the latter, whereupon switch 190 (Figure 14) may now be closed to energize the field winding 243 with direct current and then switch 189 closed to energize the 30 armature winding 240 with the alternating current, the electromagnetic system thus setting the movable lens 231 into oscillating motion.

The control or variable resistance element 187 may now be set to a value as indicated by the 35 ammeter 188 either in current intensity or by way of other indication for which the instrument may be calibrated, and then the control or resistance element 178 is progressively shifted to increase correspondingly the alternating current energizing the armature winding 240. The alternating energizing current is thus slowly increased until the indicator 204 in the circuit of the photoelectric cell gives a maximum indication, the latter corresponding to proper setting or determination of the range of movement of the movable lens 231 (Figure 13). This maximum indication of the meter or instrument 204 occurs at those points in the adjustments or settings of the control elements 178 and 187 corresponding to which 50 the range of movement of the lens 231 with respect to the remaining or stationary lenses is appropriate to bring all of the in-focus and out-of-focus images to equality of size and also to registry with one another for the scene or object being 55 photographed, since diffusion of light in the image plane and also halations, corresponding to what would be visual blurring or out-of-focus effects, are eliminated. During this time the harmonic filter 206 is cut out of the amplifier circuit of the photoelectric cell by means of its switch diagrammatically indicated at 260 in Figure 14.

Next, the light-controlling diaphragm plates 120, 121, 122 and 123 (Figures 11 and 13), having 65 already been approximately set, may now be precisely set by manipulating the thumbscrews 154, relative to the setting of the iris diaphragm, the latter being now also set with precision. The oscillation of the movable lens 231 is halted as by 70 opening switch 189, and the effects of these adjustments or settings of the iris diaphragm and of the light-varying or controlling plate members gaged with reference to their respective effects upon the photoelectric cell and its circuit. 75

In the first place, the iris diaphragm is set to make sure that sufficient light falls upon the sensitized camera element or film as is necessary to photograph the most distant objects in the particular scene, this adjustment being preferably made with the diaphragm plates 120, 121, etc., motionless, as by opening switch 195. Here again, the indicator 204 may be appropriately calibrated in terms of suitable factors, such as the distance of the most remote points in the scene or object.

Having thus achieved a precise setting of the iris diaphragm, for the particular conditions to be met, the diaphragm plates 120, 121, etc., are again set in motion and rheostats or control elements 191 and 196 (Figure 14) are manipulated one with respect to the other until the indicator or meter 204 reaches a maximum, such as indication corresponding to proper or optimum positioning of these movable elements.

Thereafter, the lens 231 is set in motion and thus the entire regulating and moving system is in action and now switch 260 of the harmonic filter 206 is actuated to bring the filter into the circuit and the above-mentioned adjustments of the diaphragm plates 120, 121, etc. is now checked. If the indicator 204 now indicates a minimum, determined by way of manipulating either or both of rheostats 191 and 196, the system is in appropriate setting and is ready for operation. The photographing of the scene or object may now be proceeded with.

In connection with the lens system of Figures 5 and 12, I described above how the lens-moving system may be set to permit selection at will of any desired range of change of focus and in accordance with certain other features of my invention, I may achieve, with the lens system of Figure 13 and its control system of Figure 14 a similar selection at will of the particular range in the scene throughout which the focus or plane of sharpness is to be changed or shifted. This I achieve by mounting on the yieldable or spring support 237 (Figure 13) which carries the movable lens 231, an electromagnet in the form of a ring-shaped or annular armature or field core 261 and provide it with a winding 262. The ring or frame support 244, made of a non-magnetic material, such as brass, is suitably recessed as at 244^a to accommodate the electromagnet 261—262 and also to accommodate a coacting electromagnet in the form of a ring or annular armature or core 263 provided with a winding 264.

These two electromagnets are thus appropriately juxtaposed to each other for appropriate coaction and in Figure 14 they are diagrammatically indicated by their windings 262 and 264, being shown connected in parallel through a control means, such as a rheostat 265, an indicating device, such as an ammeter 266, and a switch 267, to the source of direct current, such as the rectifier 186. One of these coils, such as coil or winding 262, is connected in this circuit through a reversing switch 268.

Accordingly, if these two electromagnets are energized so as to oppose to each other like poles, electromagnet 261—262 (Figure 13) is repelled by the stationary electromagnet 263—264 and hence the spring mounting or support provided by the spring supporting member 237 is biased toward the right, as viewed in Figure 13, and hence the movable lens 231 is made to assume a different normal and neutral position than it did theretofore. Accordingly, the actual range throughout

which the lens 231 is subsequently oscillated under the control of windings 243 and 240 above described is shifted to the right and the lens system, instead of changing the focus from a point near the camera to a point infinitely remote from the camera (as it would if it operated throughout its normal or complete movability of the movable lens) now changes the focus throughout a smaller range but at one end of its original or complete range of movement. By causing the two electromagnets that thus bias the spring support 237 to have opposite polarities rather than like polarities, as by operating the switch 268 (Figure 14) to reverse the current in winding 262, the two electromagnets 261—262 and 263—264 (Figure 13) now set up a force of attraction rather than repulsion and spring support 237 becomes biased toward the left; thereby a range of change of focus comprising only a portion at the other end of the original or complete range of change takes place.

In either case, of course, the intensity of energization of the biasing magnet windings and the intensity of energization of the windings 240 and 243 of the lens-moving magnet are appropriately correlated one with respect to the other and preferably by means of the photo cell circuit and related apparatus, all as was above described in detail.

Thus, the lens system of Figure 13 may be made to concentrate its unique actions of change in focus without change in size of image, throughout any desired depth of field whether that depth of field is near the camera or in the more remote portion or portions of the scene or object. Scenes or portions of scenes of smaller depth that require equal movements of the movable lens 231 to either side of its normal neutral optical position with respect to the remaining lenses may be photographed by open circuiting the biasing magnet windings 262 and 264, as by opening switch 267, and appropriately adjusting rheostats 178 and 187 give the movable lens 231 a smaller range of oscillation or of movement, thereby concentrating the action of the lens system in changing focus while maintaining size of in-focus and out-of-focus images, throughout a corresponding depth of scene positioned at a point intermediate of nearness to and remoteness from the camera. In any such case, the indicating instruments 181, 188 and 266 may be calibrated in appropriate terms to facilitate selection at will of the range of action of the lens system and the location of that desired range of action within the entire available capacity or range of action of the lens and control system.

In connection with both illustrative embodiments of my invention, I have indicated by way of illustration that I may employ a 60-cycle alternating current and that, therefore, the lens movements are such that the lens or lenses partake of sixty complete oscillations per second, each oscillation comprising two strokes of movement in opposite directions. Where my invention is embodied in a motion picture camera I need not synchronize the lens movements with the frequency or rate of exposure of film frames, the latter rate being usually about twenty-four frames per second. In such case the movable lens or lenses are certain to pass through more than one complete cycle of movement of their own for each frame exposure and thus the recording on the film of registering in-focus and out-of-focus images throughout the selected range of change of focus is assured.

On the other hand and if it is desired to substantially synchronize lens movement with frame exposure, the frequency changer 172 of Figure 14 is brought into action to change the frequency of the system to match, or become a multiple of, the frequency of film-frame exposure; where the latter is twenty-four per second, the output of the frequency changer 172 may be, for example, twenty-four, forty-eight, or the like, cycles per second. If such a change in frequency is resorted to, then the various filters above described are, of course, correspondingly adjusted to filter out or suppress frequencies above the selected frequency.

However, I have discovered that with the aid of my lens control and lens-moving system, I am enabled materially, if not entirely, to avoid so-called halation, caused, as is known, by reflection or refraction of light on or within the film itself. In that connection and referring to Figures 12 and 14, I energize the armature winding or windings of the movable parts with an alternating current of a frequency comparatively high in order thereby to cause the movable lens or the movable lenses (as well as the light-varying diaphragm plates, where those are employed) to move at faster rate of oscillation and to partake of several cycles of movement during each exposure. The effect of that action is to "eclipse" at high frequency the images projected upon the exposed camera element or film, bearing in mind that, as the lens system shifts the focus from one plane of sharpness to another, light from the object or points within that one plane of sharpness is, in effect, cut off and light coming from the object or points in the other plane of sharpness is what is directed onto the film. The higher the frequency of this eclipsing action, the less dense will be the light striking the film per cycle of the frequency of eclipsing.

Accordingly, by materially increasing the frequency of oscillation of the movable lens of Figure 13 or of the movable lens of Figure 5, I am enabled to achieve a high frequency of effective eclipsing action with corresponding lessening of density of light per eclipsing cycle; with the density of the light thus diminished, and with the above-mentioned halation effects substantially proportional to the density of the light striking the film, I am thus enabled materially to minimize or negative halation effects and hence the recording thereof. Accordingly, it is desirable to operate the system at a frequency that is a substantial multiple of the illustrative sixty cycles above set forth. And also, it is to be noted that in such case the various filters above-mentioned are provided with suitable means for adjusting them to suppress frequencies higher than the selected or operating frequency. Such factors as the distribution of mass of vibrating elements, the stiffness or resiliency of spring supports, the electrical impedance of the various alternating current circuits may be modified, changed or readjusted in any suitable way, if necessary, to suit the new condition or conditions of frequency of alternating current employed.

As earlier above noted, the source of variable or selectable frequency, diagrammatically indicated in Figures 12 and 14 at 172, may take any suitable form, but I might note that a convenient and preferred form of apparatus 172 comprises any appropriate so-called "oscillator" made up of a suitable electronic conduction tube or means with appropriate circuits, preferably variable and preferably including an amplifier, to produce a source

of alternating potential or current of selectable frequency. With such a preferred form of apparatus a relatively wide range of change of frequency may be made ready and conveniently available without detracting from the various other numerous advantages of the system and apparatus.

In this connection, the action of the lens system may be further modified to achieve certain further unique actions and results. For example, by selecting a high frequency, thereby to achieve lens oscillation at correspondingly high frequency, the effect of the lens system is to record upon the sensitized camera element or film a resultant image that is sharper than the image recorded where a lower frequency of energization and hence a lower frequency of lens oscillation is made effective. Accordingly, I make it possible to vary the sharpness of recording according to practical requirements and where motion picture photography is involved the operator may thus, by appropriately changing or selecting the frequency of energization, speedily and quickly determine the lens action to suit the technique, style or artistry desired for the particular scene, person, or object being photographed.

The photoelectric cell and its associated testing circuits may, of course, be utilized from time to time to check the initially selected settings or selection of action of the various parts, though it might be pointed out that, with the inclusion in the circuit arrangements of the voltage regulators and filters such as the regulator 175 and filter 177 of Figures 12 and 14, such subsequent checking need not be resorted to inasmuch as these parts insure that the action of the lens system and its various controls, when once selectively set as described above, remains invariable under normal operating conditions; the regulator insures the absence of voltage fluctuations and in coaction with the filter insures a steadiness of power flow that maintains steadfast the initially selected operating conditions. The filter, moreover, insures a suppression of distortion of wave shape and thus contributes toward insuring steadiness and constancy of action. The foregoing assumes, of course, normal operating conditions of temperature of the various electrical parts, particularly the field windings and armature coils of the various moving parts.

A particular advantage is achievable by way of the system of Figure 13. Should the frequency of oscillation of the movable lens or lens group bring about sound effects, due principally to the frequency of oscillation entering well into the range of audio frequencies, such sound effects may be negated in any suitable way; in that connection and as appears better in Figure 13, use may be made of the structural features whereby the space in which the moving parts, such as the lens 231 and the spring support 237, are totally enclosed as by the member 235 with the lenses 232 and 233 carried by it, and by the member 248 and the lens 230 carried by it, and if desired the resultant sealed space may be evacuated in any suitable manner, thus insuring the absence of sound-transmitting effects.

With respect to both illustrative embodiments, namely those of Figures 5 and 13, it is to be noted that any such sound effects are furthermore substantially or entirely eliminated due to the features of construction embodied in the spring lens mountings, such as those shown in Figures 9 and 10; the disk-like members there shown will be seen, as earlier described, to contain cut away or

apertured portions and thereby effectively diminish or negative the possibility of setting up sound waves through the atmosphere.

These considerations are of interest in connection with the practicing of my invention in the motion picture field or broadcasting where the process of photographing or of image production or reproduction is accompanied by a recording or broadcasting of accompanying sound or sound effects.

I have earlier above described the casing construction 58 (Figures 1, 2, 5 and 7) as including a cylindrical casing part; the latter may be closed at its right-hand end by certain of the structures already above described in detail, such as the ring mounting plate 124 of Figure 5 or the mounting plate 250 of Figure 13; the right-hand ends, however, of these mounting members are closed by a casing counterpart structure illustratively in the form of a sheet metal member 270 shaped in any suitable way to closely mate with the exterior of the contour of the ring-like mounting plate and its various lugs or projecting parts, thus to substantially enclose the operating mechanisms carried by the mounting plate. This casing counterpart 270 is provided with an aperture 271, preferably circular, having its axis coincident with the optical axis of the lens or lens system, the aperture 271 being of appropriate size or diameter to pass therethrough sufficient light from the scene or object for appropriate action or control by various of the parts, as already above described. Member 270 thus also functions as a shield for the light-controlling means or units and its exterior may be employed as a mounting plate for various accessories applied to camera and the like for producing various effects, effects such as, for example, are known in the motion picture camera art.

Thus, it will be seen that there has been provided in this invention a photographic method and apparatus in which the various objects hereinbefore noted, together with many thoroughly practical advantages, are successfully achieved. It will be noted that precision of control and action are easily achievable and that a wide range of flexibility or change or selection of action has been made possible; furthermore, it will be seen that the method and apparatus are well adapted to meet the widely varying conditions of practical use.

As many possible embodiments may be made of the mechanical and electrical features of the above invention and as the art herein described might be varied in various parts, all without departing from the scope of the invention, it is to be understood that all matter hereinabove set forth, or shown in the accompanying drawings, is to be interpreted as illustrative and not in a limiting sense.

I claim:

1. In apparatus of the character described, in combination, a lens system having a plurality of lenses axially alined and between which relative axial movement may take place and which are corrected to produce, at the image plane of said system and for a certain range of said relative movement, equality of size and registry of in-focus and out-of-focus images of a scene or object corresponding to a plurality of different planes of sharpness, means mounting said lenses in axial alinement and including means movably mounting at least one lens of said lens system for movement axially to effect said relative axial movement, said mounting means for said movable lens

comprising a yieldable disk-like member having means for securing said lens thereto at its axis and means for peripherally anchoring said disk-like member, a source of electromotive force, electromagnetic means energized from said source and including a movable part operatively associated with said disk-like member for causing the latter to yield in a direction transverse to its plane and hence to move said movable lens and means for controlling the conversion of energy from said source of electromotive force by said electromagnetic means into movement of said movable part and to maintain movement thereby of said movable lens within the aforesaid range of relative movement, thereby to cause said lens system to effect registry of said in-focus and out-of-focus images.

2. In apparatus of the character described, in combination, a lens system having a plurality of lenses axially alined and between which relative axial movement may take place and which are corrected to produce, at the image plane of said system and for a certain range of said relative movement, equality of size and registry of in-focus and out-of-focus images of a scene or object corresponding to a plurality of different planes of sharpness, means mounting said lenses in axial alinement and including means movably mounting at least one lens of said lens system for movement axially to effect said relative axial movement, said mounting means for said movable lens comprising a yieldable disk-like member having means for securing said lens thereto at its axis and means for peripherally anchoring said disk-like member whereby said movable lens, upon yielding of said disk-like member, moves along the optical axis of said lens system, means producing a unidirectional magnetic field, means producing a periodically varying magnetic field subjected to the influence of said first-mentioned magnetic field, means operatively connecting one of said field-producing means to said disk-like member whereby the latter flexes and the movable lens is moved in accordance with the interaction of said two fields, and means for controlling the interaction of said two fields to achieve movement of said movable lens within such a range of movement relative to the remaining lenses that said in-focus and out-of-focus images are in registry.

3. In apparatus of the character described, in combination, a lens system having a plurality of lenses axially alined and between which relative axial movement may take place and which are corrected to produce, at the image plane of said system and for a certain range of said relative movement, equality of size and registry of in-focus and out-of-focus images of a scene or object corresponding to a plurality of different planes of sharpness, means mounting said lenses in axial alinement and including means movably mounting at least one lens of said lens system for movement axially to effect said relative axial movement, said mounting means for said movable lens comprising a yieldable disk-like member having means for securing said lens thereto at its axis and means for peripherally anchoring said disk-like member whereby said movable lens, upon yielding of said disk-like member, moves along the optical axis of said lens system, said disk-like member having operatively connected thereto a ring-like armature with an energizing winding thereon for producing a magnetic field, magnetic-field-producing means coacting with said armature and winding to effect move-

ment of said armature and hence of said member and movable lens, the resultant movement of said movable lens being dependent upon the relative strengths of the magnetic field produced by said last-mentioned means and of the magnetic field produced by said energizing winding and ring-like armature, and control means for preventing the relative strengths of said two magnetic fields from assuming such values as would cause the resultant relative lens movement to overstep said aforesaid range of relative movement, whereby said lens system is maintained in a condition to effect said equality of size and registry of in-focus and out-of-focus images.

4. In apparatus of the character described, the combination with a lens system having a plurality of lenses axially alined and between which relative axial movement may take place and which are corrected to produce, at the image plane of said system and for a certain range of said relative movement, equality of size and registry of in-focus and out-of-focus images of a scene or object corresponding to a plurality of different planes of sharpness, said lens system having a plurality of supports for said lenses for mounting the latter in said axial alinement and including lens movably mounting at least one of said lens supports for movement thereof and of its lens axially to effect said relative axial movement, actuating means operatively connected to at least said movable lens support for effecting movement thereof and for effecting said relative axial movement in recurring cycles, of means for setting the range of relative axial movement effected by said actuating means, light-sensitive means positionable at said image plane of said lens system to receive light from said scene or object as said light is affected by said relative axial lens movement in said recurring cycles throughout the range determined by said range-setting means, and indicating means connected to said light-sensitive means and responsive to the presence or absence of modulation, at the frequency of said recurring cycles, of light striking said light-sensitive means in accordance, respectively, with the absence or presence of registration and substantial equality of said in-focus and out-of-focus images, whereby to determine whether or not said range-setting means has brought said relative lens movement within the aforesaid range of movement.

5. In apparatus of the character described, the combination with a lens system having a plurality of lenses axially alined and between which relative axial movement may take place and which are corrected to produce, at the image plane of said system and for a certain range of said relative movement, equality of size and registry of in-focus and out-of-focus images of a scene or object corresponding to a plurality of different planes of sharpness, said lens system having a plurality of supports for said lenses for mounting the latter in said axial alinement and including means movably mounting at least one of said lens supports for movement thereof and of its lens axially to effect said relative axial movement, actuating means operatively connected to at least said movable lens support for effecting movement thereof and for effecting said relative axial movement in recurring cycles, of means for setting the range of relative axial movement effected by said actuating means, a photo-electric cell and associated energizing circuit, said cell being positioned at said image plane of said lens system to receive light from said scene or object

as said light is affected by said axial lens movement in said recurring cycles throughout the range determined by said range-setting means, and means in said circuit for translating the presence, absence or degree of modulation resulting from said relative axial movement between said lenses of light reaching said cell.

6. In apparatus of the character described, in combination, a lens system having a plurality of lenses axially alined and between which relative axial movement may take place and which are corrected to produce, at the image plane of said system and for a certain range of said relative movement, equality of size and registry of in-focus and out-of-focus images of a scene or object corresponding to a plurality of different planes of sharpness, means mounting said lenses in axial alinement and including means movably mounting at least one lens of said lens system for movement axially to effect said relative axial movement, said apparatus having means for successively presenting frames of a motion picture film at the image plane of said lens system, means capable upon actuation of varying the amount of light passed by the lens system to the image plane of the latter, a source of alternating current of a frequency greater than the frequency at which said frames are successively presented at said image plane, two electromagnetic means each connected to be energized from said source and each having reciprocable means capable of reciprocation at a rate which is a function of the frequency of the alternating energizing current, means operatively connecting one of said reciprocable means to said mounting means of said movable lens and means operatively connecting the other of said reciprocable means to said light-varying means, whereby said relative lens movement and the variation of the amount of light are maintained synchronized.

7. In apparatus of the character described, in combination, a lens system having a plurality of lenses axially alined and between which relative axial movement may take place and which are corrected to produce, at the image plane of said system and for a certain range of said relative movement, equality of size and registry of in-focus and out-of-focus images of a scene or object corresponding to a plurality of different planes of sharpness, means mounting said lenses in axial alinement and including means movably mounting at least one lens of said lens system for movement axially to effect said relative axial movement, a source of electromotive force, electromagnetic means operatively connected to said mounting means of said movable lens and energized from said source for effecting movement of said movable lens and means for varying the action of said electromagnetic means to give said movable lens a range of movement within that throughout which registry of said in-focus and out-of-focus images takes place.

8. In apparatus of the character described, in combination, a lens system having a plurality of lenses axially alined and between which relative axial movement may take place and which are corrected to produce, at the image plane of said system and for a certain range of said relative movement, equality of size and registry of in-focus and out-of-focus images of a scene or object corresponding to a plurality of different planes of sharpness, means mounting said lenses in axial alinement and including means movably mounting at least one lens of said lens system for movement axially to effect said relative axial move-

ment, a source of electromotive force, electromagnetic means operatively connected to said mounting means of said movable lens and energized from said source for oscillating said movable lens, said electromagnetic means having the characteristic of changing the stroke of oscillation with change in energization thereof, and calibrated means for determining the energization of said electromagnetic means in accordance with the desired stroke of oscillation of said movable lens.

9. In apparatus of the character described, in combination, a lens system having a plurality of lens elements between which relative axial movement may take place and which are corrected to produce, at the image plane of said system and for a certain range of said relative axial movement, equality of size and registry of in-focus and out-of-focus images of a scene or object corresponding to a plurality of different planes of sharpness, said lens system having means mounting said lens elements in axial alinement and for relative axial movement and capable, when actuated, of effecting said relative axial movement, actuating means operatively connected thereto for effecting said relative axial movement in recurring cycles, control means capable, when actuated, of determining the range of said relative movement between said lens elements effected by said actuating means, photo-cell light-responsive means positioned to receive light passing from said scene or object through said lens system during said relative movement whereby light striking said light-responsive means is or is not modulated at substantially the frequency of said recurring cycles according as said relative axial movement oversteps or is within said certain range, and translating means connected to said light-responsive means and responsive to the reaction of the latter to the presence or absence of modulation of said light at the aforesaid frequency according as said relative axial movement oversteps or is within said certain range and hence according to absence and presence respectively of equality of size and registry of in-focus and out-of-focus images.

10. An apparatus as claimed in claim 9 in which the means mounting the lens elements in axial alinement and for relative movement comprises movable lens mounts, one for each of such lens elements of said lens system as are movable, and the actuating means for effecting said relative movement comprises electromagnetic means, one for each of said movable lens mounts, and having operative connections therewith respectively for effecting movement thereof, and in which said control means comprises means for controlling the action of said electromagnetic means and hence for determining the range of relative movement between the lens elements.

11. An apparatus as claimed in claim 9 in which the means mounting the lens elements in axial alinement and for relative movement comprises movable lens mounts, one for each of such lens elements of said lens system as are movable, and the actuating means for effecting said relative movement comprises electromagnetic means, one for each of such of the lens elements as is movable for effecting movement of said movable lens mounts and having operative connection therewith, means operating upon said electromagnetic means to maintain movement of said movable lens mounts in said recurring cycles but in step with one another, and in which said control means comprises means for controlling the action

of and hence the range of movement effected by said electromagnetic means.

12. An apparatus as claimed in claim 9 in which the means mounting said lens elements in axial alinement and for relative movement comprises lens-mounting means for certain of said lens elements and means for holding them fixed in position and a movable lens mount for at least one of said plurality of lens elements, whereby said relative movement is effected by movement of said movable lens mount, and in which said actuating means for effecting said relative movement between said lens elements comprises electromagnetic means operatively connected with said movable lens mount for effecting movement of said movable lens and in which said control means comprises means for controlling the action of said electromagnetic means whereby said relative movement may be brought within said certain range. 10 15 20

13. An apparatus as claimed in claim 9 in which the means mounting said lens elements in axial alinement and for relative movement comprises lens-mounting means for certain of said lens elements and means for holding them fixed in position and a movable lens mount for at least one of said plurality of lens elements, whereby said relative movement is effected by movement of said movable lens mount, and in which said actuating means for effecting said relative movement between said lens elements comprises electromagnetic means which has operative connection with said movable lens mount and which when energized gives said movable lens a back and forth movement in said recurring cycles and in which said control means comprises means for controlling said electromagnetic means to change the range of said back and forth movement. 35

14. An apparatus as claimed in claim 9 in which the means mounting said lens elements in axial alinement and for relative movement comprises lens-mounting means for certain of said lens elements and means for holding them fixed in position and a movable lens mount for at least one of said plurality of lens elements, whereby said relative movement is effected by movement of said movable lens mount, and in which actuating means for effecting said relative movement between said lens elements comprises electromagnetic means which has operative connection with said movable lens mount and which when energized gives said movable lens a back and forth movement in said recurring cycles, means for changing the frequency of said recurring cycles, and in which said control means comprises means for controlling said electromagnetic means to change the range of said back and forth movement. 40 45 50 55

15. An apparatus as claimed in claim 9 in which said light-responsive means comprises a light-sensitive electric cell having an output circuit in which is connected a suitable source of potential and in which said translating means is an electro-responsive device connected in said output circuit and is responsive to modulations of electrical energy in said output circuit corresponding to modulations in the response of said cell to light modulations at the frequency of said recurring cycles caused by said absence of registry of said in-focus and out-of-focus images. 60 63 70

16. In apparatus of the character described, in combination, a lens system having a plurality of lens elements between which relative axial movement may take place and which are corrected to 75

produce, at the image plane of said system and for a certain range of said relative movement, equality of size and registry of in-focus and out-of-focus images of a scene or object corresponding to a plurality of different planes of sharpness, means mounting said lens elements in axial alinement and capable, when actuated, of effecting said relative axial movement, actuating means therefor comprising electromagnetic means having operative connection therewith for effecting relative movement between said lens elements as aforesaid and within said certain range, and electromagnetic means positioned to react upon said first-mentioned electromagnetic means for causing the latter to effect relative movement throughout only a portion of said certain range of relative movement.

17. In apparatus of the character described, in combination, a lens system having a plurality of lens elements between certain of which relative movement may take place and which are corrected to produce, at the image plane of said system and for a certain range of relative movement, equality of size and registry of in-focus and out-of-focus images of a scene or object corresponding to a plurality of different planes of sharpness, means mounting said lens elements in axial alinement and including movable means capable upon actuation of effecting relative axial movement between said lens elements and within said certain range, means at the image plane of said system for receiving registered in-focus and out-of-focus images of said scene or object, electromagnetic means having operative connection with said movable means and capable of energization by a periodically varying current and when so energized for effecting said relative movement in recurring cycles of a frequency that is a function of the frequency of variation of said current, means forming a source of periodically varying current, and means connecting said source to said electromagnetic means to energize the latter.

18. An apparatus as claimed in claim 17 in which there is provided means for changing the frequency of variation of said energizing current in order thereby to change the frequency of said cycles of relative movement.

19. In apparatus of the character described, in combination, a lens system having a plurality of lens elements between certain of which relative movement may take place and which are corrected to produce, at the image plane of said system and for a certain range of relative movement, equality of size and registry of in-focus and out-of-focus images of a scene or object corresponding to a plurality of different planes of sharpness, means mounting said lens elements in axial alinement and including movable means capable upon actuation of effecting relative axial movement between said lens elements and within said certain range, means for holding at said image plane a sensitized photographic element for recording said images of said scene or object when said photographic element is exposed, means for effecting exposure of said photographic element, and means operating upon said movable means to effect said relative movement in recurring cycles of high frequency during the exposure of said photographic element and thereby to negative halation effects in the latter.

20. The method of determining the desired relative axial movement between a plurality of lens elements of a lens system which are corrected to produce, at the image plane of said system and for a certain range of relative axial

movement, equality of size and registry of in-focus and out-of-focus images of a scene or object corresponding to a plurality of different planes of sharpness, which comprises effecting relative movement between said lens elements during exposure of said lens system to a scene or object, causing light from said lens system to strike a photo-cell light-responsive device positioned at the image plane of said lens system, translating the reaction of said device to said light into components at least one of which, if not reduced to zero or substantially so, corresponds to a modulating effect caused by non-registry of said in-focus and out-of-focus images, and changing said relative movement in a direction to reduce said one component if present to substantially zero.

21. The method of determining the desired relative axial movement between a plurality of lens elements of a lens system which are corrected to produce, at the image plane of said system and for a certain range of relative axial movement, equality of size and registry of in-focus and out-of-focus images of a scene or object corresponding to a plurality of different planes of sharpness, which comprises effecting relative movement between said lens elements during exposure of said lens system to a scene or object, translating the light effects transmitted to said image plane by said lens system into electrical energy, detecting in the latter modulations that are a function of the non-registry, if present, of in-focus and out-of-focus images of said scene or object, and modifying said relative movement in a direction to cause said translated electrical energy to be devoid of a modulation of the aforesaid character.

22. In apparatus of the character described, in combination, a lens system having a plurality of lens elements between which relative axial movement may take place and which are corrected to produce, at the image plane of said system and for a certain range of said relative axial movement, equality of size and registry of in-focus and out-of-focus images of a scene or object corresponding to a plurality of different planes of sharpness, means mounting said lens elements in axial alinement and including oscillatable means capable upon actuation of effecting relative axial movement between said lens elements and within said certain range, said apparatus having means for successively presenting and exposing frames of a motion picture film at the image plane of said system, means forming a source of alternating current energy of a frequency greater than the frequency of presentation and exposure of said frames at said image plane, electromagnetic means energized from said source of alternating current energy and having a movable part that is set into motion upon energization of said electromagnetic means at a rate that is a function of the frequency of said source, and means forming operative connection between said oscillatable means and said movable part for effecting oscillation of said oscillatable means and thereby effecting said relative axial lens movement in a plurality of strokes for each frame presentation and exposure.

23. In apparatus of the character described, in combination, a lens system having a plurality of lens elements between which relative axial movement may take place and which are corrected to produce, at the image plane of said system and for a certain range of said relative movement, equality of size and registry of in-focus

- and out-of-focus images of a scene or object corresponding to a plurality of different planes of sharpness, means mounting said lens elements in axial alinement and including movable means capable upon actuation of effecting relative axial movement between said lens elements, actuating means having operative connection with said movable means for effecting said relative movement within said certain range and in recurring cycles, actuatable diaphragm means capable upon actuation of varying the amount of light passed by said lens system to the image plane thereof, actuating means for said diaphragm means for effecting light variation in recurring cycles, means causing said two actuating means to effect said relative lens movement and said varying of the amount of light synchronously, photo-cell light-responsive means positioned to receive light from said lens system, controllable means for determining the extent of actuation of said diaphragm means by its aforesaid actuating means, and translating means connected to said photo-cell means and responsive to the reaction of said photo-cell means to said light as modulated by light variation at the frequency of said recurring cycles caused by said diaphragm means with respect to the range of said different planes of sharpness of said lens system.
24. In apparatus of the character described, in combination, a lens system having a plurality of lens elements between which relative axial movement may take place and which are corrected to produce, at the image plane of said system and for a certain range of said relative movement, equality of size and registry of in-focus and out-of-focus images of a scene or object corresponding to a plurality of different planes of sharpness, means mounting said lens elements in axial alinement and including movable means capable upon actuation of effecting relative axial movement between said lens elements, actuating means having operative connection with said movable means for effecting said relative movement within said certain range and in recurring cycles, actuatable diaphragm means capable upon actuation of varying the amount of light passed by said lens system to the image plane thereof, actuating means for said diaphragm means for effecting light variation in recurring cycles, means causing said two actuating means to effect said relative lens movement and said varying of the amount of light synchronously, photo-cell light-responsive means positioned to receive light from said lens system, controllable means for determining the extent of actuation of said diaphragm means by its aforesaid actuating means, and means connected to said photo-cell means for detecting the reaction of said photo-cell means to said light to determine the effect of said light-varying means.
25. In apparatus of the character described, in combination, a lens system having a plurality of lens elements between which relative axial movement may take place and which are corrected to produce, at the image plane of said system and for a certain range of said relative movement, equality of size and registry of in-focus and out-of-focus images of a scene or object corresponding to a plurality of different planes of sharpness, means mounting said lens elements in axial alinement and including movable means capable upon actuation of effecting relative axial movement between said lens elements, actuating means having operative connection with said movable means for effecting said relative axial movement in recurring cycles, control means capable upon actuation of altering said relative axial movement and of bringing the latter within the aforesaid certain range of said relative axial movement, light-responsive electric-cell means positioned to receive light from said scene or object and passed thereto through said lens system as said actuating means effects said relative axial movement in said recurring cycles, said electric-cell means having connected thereto an output circuit with a source of suitable potential therein whereby there is made effective in said circuit a flow of electrical energy which is modulated at the frequency of said recurring cycles if the range of said relative axial movement is not within said certain range and which is substantially free from modulations of the said frequency if said relative axial movement is within said certain range, a translating device connected to said circuit and responsive to the presence or absence of modulations in the electrical energy in the said circuit, and filter means connected to said circuit for preventing said translating device from responding to modulations of the energy in said circuit caused by stray or foreign effects.
26. In apparatus of the character described, in combination, a lens system having a plurality of lens elements between which relative axial movement may take place and which are corrected to produce, at the image plane of said system and for a certain range of said relative movement equality of size and registry of in-focus and out-of-focus images of a scene or object corresponding to a plurality of different planes of sharpness, means mounting said lens elements in axial alinement and including movable means capable upon actuation of effecting relative axial movement between said lens elements, actuating means having operative connection with said movable means for effecting said relative axial movement in recurring cycles, control means capable upon actuation of altering said relative axial movement and of bringing the latter within the aforesaid certain range of said relative axial movement, light-responsive electric-cell means positioned to receive light from said scene or object and passed thereto through said lens system and having connected thereto an output circuit with a source of suitable potential therein, and an electro-responsive analyzer in said output circuit and responsive to the presence or absence of modulations, at the frequency of said recurring cycles, in the energy in said output circuit according to the light effects upon said cell means by the absence or presence of non-registry of said in-focus and out-of-focus images.
27. In apparatus of the character described, in combination, a lens system having a plurality of lenses axially alined and between which relative axial movement may take place and which are corrected to produce, at the image plane of said system and for a certain range of said relative movement, equality of size and registry of in-focus and out-of-focus images of a scene or object corresponding to a plurality of different planes of sharpness, means mounting said lenses in axial alinement and including means movably mounting at least one lens of said lens system for movement axially to effect said relative axial movement, a source of periodically varying electromotive force, electromagnetic means energized from said source for producing a periodically varying magnetic field and having movable means responsive to said varying

- magnetic field and operatively connected to said mounting means of said movable lens for effecting oscillating movement of said movable lens, and means for varying the action of said electromagnetic means to give said movable lens a range of oscillating movement within, and equal to any selectable portion of, that aforesaid certain range throughout which registry of said in-focus and out-of-focus images takes place, 5
- 5 10 15 20 25 30 35 40 45 50 55 60 65 70 75
- said varying means comprising electromagnetic means positioned to react upon said first-mentioned electromagnetic means to change the co-acting relationship between said movable means and said magnetic field, and controllable means for varying the action of said second-mentioned electromagnetic means.
28. In apparatus of the character described, in combination, a lens system having a plurality of lenses axially aligned and between which relative axial movement may take place and which are corrected to produce, at the image plane of said system and for a certain range of said relative movement, equality of size and registry of in-focus and out-of-focus images of a scene or object corresponding to a plurality of different planes of sharpness, means mounting said lenses in axial alinement and including means movably mounting at least one lens of said lens system for movement axially to effect said relative axial movement, a source of periodically varying electromotive force, electromagnetic means energized from said source for producing a periodically varying magnetic field and having movable means responsive to said varying magnetic field and operatively connected to said mounting means of said movable lens for effecting oscillating movement of said movable lens, calibrated control means for varying the energization of said electromagnetic means from said source, and means for varying the action of said electromagnetic means to give said movable lens a range of movement within, and equal to any selectable portion of, that aforesaid certain range throughout which registry of said in-focus and out-of-focus images takes place, 5
- 5 10 15 20 25 30 35 40 45 50 55 60 65 70 75
- said varying means comprising a source of unidirectional electromotive force and electromagnetic means energized therefrom and positioned to react upon said first-mentioned electromagnetic means for changing the cooperative relationship therebetween and said movable means, and calibrated control means for controlling the energization of said second-mentioned electromagnetic means for said source of unidirectional electromotive force.
29. In apparatus of the character described, in combination, a lens system having a plurality of lenses axially aligned and between which relative axial movement may take place and which are corrected to produce, at the image plane of said system and for a certain range of said relative movement, equality of size and registry of in-focus and out-of-focus images of a scene or object corresponding to a plurality of different planes of sharpness, means mounting said lenses in axial alinement and including means movably mounting at least one lens of said lens system for movement axially to effect said relative axial movement, a source of electromotive force, electromagnetic means operatively connected to said mounting means of said movable lens and energized from said source for oscillating said movable lens, said electromagnetic means having the characteristic of changing the stroke of oscillation with change in energization thereof, calibrated means for determining the energization of said electromagnetic means in accordance with the desired stroke of oscillation of said movable lens, electromagnetic means acting, when energized, to have a biasing effect upon the action of said first-mentioned electromagnetic means in oscillating said movable lens for thereby affecting the location of the aforesaid desired stroke of oscillation of said movable lens, and calibrated means for determining the energization of said second-mentioned electromagnetic means in accordance with the desired location of said desired stroke of oscillation of the movable lens.
30. An apparatus as claimed in claim 22 provided with means controllable at will for causing said electromagnetic means to oscillate said movable part in strokes of length less than said certain range and throughout any one of a plurality of portions of said certain range, thereby to effect equality of size and registry of such in-focus and out-of-focus images of the said scene or object as are in such different planes of sharpness corresponding to the selected length of strokes and selected portion of said range.
31. An apparatus as claimed in claim 22 provided with a source of direct current energy, electromagnetic means energized from said source of direct current energy to produce a uni-directional magnetic field acting upon said movable part to affect the length of said strokes of oscillation of said movable part by said first-mentioned electromagnetic means and the location of said strokes within said certain range of relative axial movement, and control means for determining the energization of said second-mentioned electromagnetic means from said source of uni-directional energy to determine the length of said strokes and the location thereof.
32. In apparatus of the character described, in combination, a lens system having a plurality of lenses axially aligned and between which relative axial movement may take place and which are corrected to produce, at the image plane of said system and for a certain range of said relative movement, equality of size and registry of in-focus and out-of-focus images of a scene or object corresponding to a plurality of different planes of sharpness, means mounting said lenses in axial alinement and including means movably mounting at least one lens of said lens system for movement axially to effect said relative axial movement, said mounting means for said movable lens comprising a yieldable disk-like member having means for securing said lens thereto at its axis and means for peripherally anchoring said disk-like member whereby said movable lens, upon yielding of said disk-like member, moves along the optical axis of said lens system, means producing a unidirectional magnetic field, means producing a periodically varying magnetic field subjected to the influence of said first-mentioned magnetic field, means operatively connecting one of said field-producing means to said disk-like member whereby the latter flexes and the movable lens is moved in accordance with the interaction of said two fields, and means for controlling the interaction of said two fields to achieve movement of said movable lens within such a range of movement relative to the remaining lenses that said in-focus and out-of-focus images are in registry, and means controllable at will for causing said two fields to effect said movement of said movable lens throughout only a portion of said certain range.

33. In apparatus of the character described, in combination, a lens system having a plurality of lenses axially aligned and between which relative axial movement may take place and which are corrected to produce, at the image plane of said system and for a certain range of said relative movement, equality of size and registry of in-focus and out-of-focus images of a scene or object corresponding to a plurality of different planes of sharpness, means mounting said lenses in axial alinement and including means movably mounting at least one lens of said lens system for movement axially to effect said relative axial movement, said mounting means for said movable lens comprising a yieldable disk-like member having means for securing said lens thereto at its axis and means for peripherally anchoring said disk-like member whereby said movable lens, upon yielding of said disk-like member, moves along the optical axis of said lens system, means producing a unidirectional magnetic field, means producing a periodically varying magnetic field subjected to the influence of said first-mentioned magnetic field, means operatively connecting one of said field-producing means to said disk-like member whereby the latter flexes and the movable lens is moved in accordance with the interaction of said two fields, and means for controlling the interaction of said two fields to achieve movement of said movable lens within such a range of movement relative to the remaining lenses that said in-focus and out-of-focus images are in registry, means producing a unidirectional magnetic field effective to bias said yieldable disk-like member and thereby affect the length of stroke of movement of said movable lens within said certain range and the location of said stroke in said certain range, and calibrated control means for said last-mentioned field-producing means to determine the desired length of said stroke and the desired location of said stroke in said certain range of movement.

34. An apparatus as claimed in claim 17 in which there is provided means for changing the frequency of variation of said energizing current in order thereby to change the frequency of said cycles of relative movement, means operative to cause said electromagnetic means to effect relative movement throughout only a portion of said certain range, and control means operable at will for controlling the action of said last-mentioned means.

35. An apparatus as claimed in claim 17 in which there is provided control means for changing the action of said electromagnetic means when energized from said source and for thereby changing the length of the stroke of said relative movement, means operative to affect the location, along the line of said certain range of movement, of the stroke of said relative movement as effected in said recurring cycles by said electromagnetic means, said means being reversible in action and, when acting in one direction, operating to limit

the location of said stroke toward one end of said certain range and, when acting in reverse direction, operating to limit the location of said stroke toward the other end of said certain range, and means for controlling the direction in which said reversible means is operative.

5

36. An apparatus as claimed in claim 17 in which there is provided control means for changing the action of said electromagnetic means when energized from said source and for thereby changing the length of the stroke of said relative movement, electromagnetic means operative to affect the location, along the line of said certain range of movement, of the stroke of said relative movement as effected in said recurring cycles by said first-mentioned electromagnetic means, said second electromagnetic means being reversible in action and, when acting in one direction, operating to cause said first electromagnetic means to effect said movement in a stroke that takes place toward one end of said certain range and, when acting in reverse direction, operating to effect said relative movement in a stroke that takes place toward the other end of said certain range, and an energizing circuit for said second electromagnetic means having included therein control means for changing the degree of its energization and control means for determining the direction in which said second electromagnetic means acts, thereby to select different lengths of stroke of said relative movement in different portions of said certain range.

10

37. An apparatus as claimed in claim 17 in which there is provided energizable electromagnetic means coacting with said first electromagnetic means and operative to affect the location, along the line of said certain range, of the stroke of said relative movement as effected in said recurring cycles by said first electromagnetic means, said second electromagnetic means being reversible in action according to the direction of flow of energizing current thereto and, when acting in one direction, operating to limit the location of said stroke toward one end of said certain range and, when acting in reverse direction, operating to limit the location of said stroke toward the other end of said certain range, calibrated manual control means for said first electromagnetic means to vary the action of said first electromagnetic means in effecting said relative movement in recurring cycles, an energizing circuit for said second electromagnetic means having included therein switch means for controlling the direction of flow of energizing current thereto for thereby determining the direction in which said second electromagnetic means is to be operative to thereby select toward which end of said range the said relative movement is to take place and calibrated manual control means for varying the energization of said second electromagnetic means.
